UNITED STATES PATENT OFFICE.

OSCAR V. BLITTERSDORFF, OF SAUGERTIES, NEW YORK, ASSIGNOR TO J.
B. SHEFFIELD & SON, OF SAME PLACE.

BOX.

SPECIFICATION forming part of Letters Patent No. 416,892, dated December 10, 1889.

Application filed April 12, 1889. Serial No. 306,949. (No model.)

To all whom it may concern:

Be it known that I, OSCAR V. BLITTERSDORFF, of Saugerties, in the county of Ulster and State of New York, have invented a certain new and useful Improvement in Boxes, of which the following is a specification.

My improvement relates more particularly to boxes made of pasteboard, and is designed to facilitate the exhibition of articles contained in the box.

In the accompanying drawings, Figure 1 is a perspective view of a box embodying my improvement, showing the box closed. Fig. 2 is a side view of a tray contained in the box. Fig. 3 is a side view of the box and showing the same open and the tray occupying a position in which the goods contained in the box may be readily examined.

Similar letters of reference designate corresponding parts in all the figures.

A designates a case or shell, rectangular in form and closed upon all of its sides and one of its ends, the other end being open.

B designates a tray. This tray comprises a bottom *a* and sides *b*. The sides *b* are inclined downwardly from their upper edges and extend to only about midway in the length of the bottom of the tray, or, in other words, they stop short of the rear end of the tray. Across the top of the tray and at the front end there will preferably extend a cross-strip *c*, as more clearly shown in dotted line in Fig. 1.

The operation of the box is more clearly shown in Fig. 3, the tray being drawn out sufficiently far or to a point at or near the point of junction between the sides and the bottom of the tray. The tray may be tipped downwardly, so that the end of the bottom *a* will contact with the upper side of the case *A*, thus retaining the tray in position. While in such position the contents of the box, which are of course upon the tray, may be readily inspected. The cross-strip *c* when used will tend to retain the contained articles upon the tray.

Very many articles—such as shirts, underwear, &c.—may be contained in the box and be very quickly and easily exhibited without being wholly removed. I have shown knobs *d* upon the front of the tray, by which the latter may be removed.

What I claim as my invention, and desire to secure by Letters Patent, is—

In a box, the combination, with a case closed upon all sides and at one end, of a sliding tray for the case adapted to be received therein, and having a bottom *a* and inclined sides *b*, terminating short of the rear end of said bottom, so that said bottom continues beyond said inclined sides, substantially as specified.

OSCAR V. BLITTERSDORFF.
